DISPLAY STAND FOR A FOOTBALL OR THE LIKE

Eli A. Robinson, Amsterdam, N.Y., assignor to Collette Manufacturing Company, Amsterdam, N.Y., a corporation of New York

Filed Nov. 18, 1966, Ser. No. 4,741

Term of patent 14 years

(Cl. D80—9)

The figure is a front perspective view of a display stand for a football or the like showing my new design, the rear being plain and unornamented.

The broken line representation of a football and kicking tee in the figure is for purposes of illustration only.

I claim:

The ornamental design for a display stand for a football or the like, as shown and described.
